UNITED STATES PATENT OFFICE.

HENRY WILLIAM TAYLOR, OF BILTON, ENGLAND, ASSIGNOR TO GENERAL ELECTRIC COMPANY, A CORPORATION OF NEW YORK.

DYNAMO-ELECTRIC MACHINE.

Application filed August 27, 1919. Serial No. 320,152.

To all whom it may concern:

Be it known that I, HENRY WILLIAM TAYLOR, a subject of the King of Great Britain, residing at Bilton, in the county of Warwickshire, England, have invented certain new and useful Improvements in Dynamo-Electric Machines, of which the following is a specification.

The present invention relates to dynamo electric machines and more particularly to armature windings for alternating current machines.

In large alternating current generators in which the windings disposed in the armature slots, consist of conductors of considerable depth, magnetic flux across the slot arising from the current in the conductors, gives rise to a parasitic voltage within the conductors which is liable to cause local currents, thereby producing heating of the conductors and the inefficient use of the copper in the armature.

It has hitherto been proposed to limit the current which will flow as a result of these parasitic voltages first of all by dividing the conductors into a number of separate multiple bars, and secondly by continuing this lamination of the complete conductor throughout the complete coil, and so connecting the ends that the order of the bars in the conductors in the upper portion of the coil is the reverse of the order of the bars in the conductors in the lower portions of the coil.

It is found, however, that on large machines, with very deep conductors, the local currents which flow even when these provisions are made, are still excessive and impose limitations on the design of the machine.

The magnetic flux which passes across the bottom conductor in a slot depends only upon the current being carried in this conductor and therefore, increases, gradually from zero at the bottom of the conductor. The flux in any other conductor nearer the mouth of the slot depends not only upon the current which that conductor is carrying, but also upon the amount of current in the conductors below the one in question. The flux across such conductor may, therefore, be considered as consisting of a variable element due to the current in that conductor and also of a constant element the

value of which depends upon the number 55 of conductors below the conductor in question; as for instance, the second conductor is subjected to the influence of one constant element of flux, the third conductor is subjected to the influence of two constant elements of flux, the fourth conductor to three constant elements of flux, and so on.

In the joint application of myself, Frederick H. Clough, and Frank P. Whitaker, Serial No. 303,101, filed June 10, 1919, there 65 is described how in a two-layer multiple turn coil, consisting of conductors with a number of bars in multiple, these bars being continuously insulated throughout the coil, the parasitic voltage arising from the constant elements of flux in the successive turns can be completely or very nearly eliminated by suitably connecting the individual bars of the conductor at the ends of the coil.

In the case of a coil in which the number 75 of turns is divisible by two, it is possible to completely eliminate the parasitic voltage due to the constant flux elements in the manner proposed in the application referred to, but in the case of a coil consisting of a number of turns not divisible by two the most perfect arrangement—in accordance with the disclosure in that application although a considerable improvement upon the previous method of constructing such coils—leaves 80 the parasitic voltage due to a single constant flux element uneliminated.

I find, however, that if the coil is so constructed that the parasitic voltage due to this uneliminated single constant flux element is placed in opposition to the parasitic voltage due to two variable flux elements, the parasitic voltage due to the single constant flux element then becomes completely 90 eliminated.

According to the present invention, therefore, in the construction of a multiple turn coil, I continuously insulate the separate bars of which the conductor consists throughout the coil, and so connect them in 100 the successive half turns of the coil that the number of variable flux elements which remain unopposed is twice the number of constant flux elements which are uneliminated, and the unopposed variable flux elements are in opposition to the uneliminated constant flux elements.

The accompanying drawing illustrates my

invention. In it I have shown a three-turn coil arranged in two slots which contain the top and bottom portions of the same coil.

It will be understood that the two slots 5 illustrated are not adjacent slots but occupy positions around the armature a full pole pitch apart or nearly a pole pitch apart according to whether the winding has a full or a fractional pitch.

10 The conductor is shown as being made up of five bars or laminations designated by the numerals 1 to 5, while the half turns of the coil are marked *a*, *b*, *c*, *d*, *e* and *f*, *a* being at the bottom of one slot while *f* is at the top 15 or mouth of the other slot. It will be seen that the bars in half turns *a*, *b*, *c* and *e* are all arranged in the same order, whereas those in *d* and *f* are in the reverse order.

In the arrangement shown, the constant 20 flux element is the flux, of uniform density, which threads the conductor comprising half turn *b*, that is, which is confined between the top and bottom of this conductor, and is due entirely to the magnetomotive force 25 below this conductor. The variable flux element is the flux, of a density increasing toward the mouth of the slot, which threads the conductor comprising half turn *b* and is due solely to the current in conductor *b*.

30 In order to set forth clearly and simply how the parasitic voltages are induced and the manner in which these voltages tend to cause current to flow, let it be assumed for the moment that the laminations of the 35 conductor comprising half turn *b* are connected in multiple at the ends of this half turn instead of being connected in multiple at the ends of the complete three-turn coil only. A given alternating current in the

40 conductor comprising half turn *a* will cause an alternating flux to thread into and out of the conducting circuit or coil formed by laminations 1 and 5 which we have just assumed to be connected at their ends. This 45 alternating flux induces an alternating electromotive force in the circuit comprising laminations 1 and 5 and this electromotive force is termed a parasitic voltage since it tends to circulate a local or 50 useless current. Of course, there is a similar tendency to circulate current between laminations 2 and 4, and between other laminations, but it is believed that the explanation with reference to laminations 1 and 5 will 55 be sufficient to enable the action to be fully understood. The flux threading the slot above half turn *a* due to the current in *a* alone is uniformly distributed throughout the area of the slot and, therefore, the flux 60 threading the conductor comprising half turn *b* and due to the current in *a* does not vary from point to point from the bottom toward the top of the conductor but is at any given instantaneous value of the cur-

65 rent in half turn *a* constant for every point

in the conductor comprising half turn *b*. This element of flux I have termed the constant flux element. Since there is but one half turn below half turn *b*, the parasitic voltage in *b* is due to but one constant flux 70 element. It is obvious that the parasitic voltage induced in *c* due to the half turns below *c* would be twice as great since this voltage would be caused by two equal constant flux elements due respectively to *a* and *b*. With this explanation of the action of the constant flux element in producing a parasitic voltage, it is believed that the action of the variable flux element in inducing a parasitic voltage will be obvious. Bearing 75 in mind that the laminations are not connected together at the end of each half turn but only at the end of the coil, it at once appears that the circulating currents which flow are due only to the resultant of 80 the parasitic voltages induced in every half turn of the complete coil.

It will be noted that there are four variable flux elements, due respectively to half turns *a*, *b*, *c* and *e* which produce parasitic 85 voltages in the same direction, while there are but two variable flux elements, due to half turns *d* and *f* respectively, which produce parasitic voltages in the opposite direction. There are, therefore, two unbalanced variable flux elements in favor of the 90 first group of half turns. The constant flux elements in half turns *a*, *b*, *c* and *e* are equal to zero, one, two and four respectively, making a total of seven, while those in the 95 second group *d* and *f* equal three and five respectively, making a total of eight, thus leaving a balance of one uneliminated constant flux element in the second group.

The single uneliminated constant element 100 in the second group of half turns is therefore in opposition to the two unopposed variable elements in the first group of half turns and in this way the tendency for the uneliminated constant flux element to produce 105 parasitic currents in the whole of the conductors of the coil is neutralized.

When the winding has a fractional pitch the half turns of the upper portion of the coil are subjected to the external influence 110 from the conductors in the bottom of the same slot which is not in phase with their own current. I find, however, that a considerable improvement is effected in the elimination of eddy currents in this case as 115 compared with the construction hitherto in use, although the improved construction does not entirely eliminate the constant flux element.

What I claim as new and desire to secure 120 by Letters Patent of the United States, is:—

1. An armature winding comprising a conductor composed of a plurality of laminations insulated throughout the coil and connected in multiple at the ends of the 125

- coil, the order of arrangement of the laminations of some of the half turns in a coil being similar and the opposite of the order of arrangement of the laminations in other 5 half turns of the coil, the number of half turns in each group being chosen so as to balance as nearly as possible the parasitic voltages due to the constant flux elements in all of the half turns of the coil, the order 10 of the laminations at the same time being chosen so that any unbalanced parasitic voltage due to constant flux elements is opposed by the parasitic voltage due to double the number of variable flux elements.
- 15 2. A two layer armature winding having three turns per coil, comprising a conductor composed of a plurality of laminations insulated throughout the coil and connected in multiple at the ends of the coil, the order 20 of arrangement of the laminations in the three half turns in the bottom side of the coil being the same and the same as the order of arrangement of the laminations in the middle half turn of the top side of the
- coil, the order of arrangement of the laminations in the remaining two half turns of the top side of the coil being the reverse of that in the other half turns. 25
3. In an alternating current dynamo electric machine, an armature winding comprising coils having an odd number of turns, each coil being composed of a plurality of insulated laminations, characterized by the fact that the laminations of the half turns are arranged in such a manner that the number of variable flux elements which remain unopposed is twice the number of constant flux elements which are uneliminated, the unopposed, variable flux elements being in opposition to the uneliminated constant flux 30 elements. 35
- In witness whereof, I have hereunto set my hand this eighth day of August, 1919.

HENRY WILLIAM TAYLOR.
